[57] **ABSTRACT**

In a spent photographic silver bleach solution the ratio of ferrocyanide to ferricyanide has attained a value at which the efficacy of bleaching is so greatly impaired that the solution must be either discarded or regenerated. According to the present disclosure, regeneration is accomplished with an alkali metal halite that reacts with the ferrocyanide to oxidize it to a ferricyanide. The reaction takes place at a pH between about 6 and about 8. An acid preferably is present to prevent the reaction conditions from becoming so alkaline as to materially inhibit the oxidation.

METHOD OF REGENERATING A SPENT PHOTOGRAPHIC SILVER BLEACH SOLUTION

BACKGROUND OF THE INVENTION

1. Field of the Invention

Regeneration of a spent photographic silver bleach solution.

1. Description of the Prior Art

Bleach solutions are widely used in certain branches of photography. They are employed to remove metallic silver grains from an emulsion in which they were formed by development of exposed particles of silver halide. Typically, the bleaching is performed in color film processes to remove metallic silver grains the presence of which is necessary to permit the formation of colored dye images, and in reversal black and white processes to remove the silver grains which formed the negative image prior to the re-exposure of film for ac-tinically sensitizing the remaining particles of silver halide. The purpose of bleaching is to convert the metallic silver into a silver salt which thereafter is made water soluble by fixation (treatment with thiosulfate) and subsequently removed from the film by washing with water. Although the conversion of metallic silver to the silver salt occurs in several steps the particular reaction is not important to the discussion of this invention and, therefore, only the overall simplified ionic equation is given below:

A commonly and widely used bleach solution contains as the oxidizing agent an alkali metal ferricyanide and an alkali metal bromide to effect the reaction above given, and usually other ingredients such as bleach accelerators (see, for example, British Pat. No. 1,150,466), buffers (see, for example, U.S. Pat. No. 3,342,598), corrosion inhibitors (see, for example, British Pat. 872,275), anti-sludge agents, and biocides (see, for example, British Pat. 1,177,048). The particular constitution of the bleach solution is of no particular importance to the present invention as long as it contains ferricyanide which is in part reduced to ferrocyanide during the bleaching process. As just implied, the ferricyanide oxidizes metallic silver to silver in its ionic form which thereupon reacts with the bromide ion to form the sparingly soluble silver bromide. As the ferricyanide oxidizes the metallic silver, the ferricyanide itself is reduced to ferrocyanide.

Ferrocyanide accumulates in the bleach solution. The decrease in ferricyanide and the corresponding increase in ferrocyanide gradually impairs the efficacy of the bleach until finally a point is reached where the solution no longer is commercially effective and either must be discarded or it must be regenerated.

At this point there still is a preponderance of ferricyanide. It is only the ferrocyanide which must be regenerated by converting the same back to ferricyanide. The actual ratio between the two cyanides has no bearing upon the use of the present invention and, indeed, the limiting ratio beyond which the solution should not be used will depend upon various other factors such, for example, as the solution temperature and the bleach accelerators employed. Mention has been made of the spending of ferricyanide simply in order to understand the manner in which the ferrocyanide came into being and the necessity of restoring ferrocyanide to ferricyanide when the occasion requires. Such ne-

cessity for regeneration long has been recognized in the photographic art and the specific regeneration of ferrocyanide to ferricyanide has been practiced for many years.

5 At one time, an electrolytic method was employed for this purpose, but because of its high maintenance costs and operational problems it was abandoned.

A number of chemical agents have been proposed to oxidize ferrocyanide to ferricyanide. Thus, liquid bromine is disclosed for this purpose in U.S. Pat. No. 2,515,930. But bromine is caustic and corrosive and, hence, great caution must be exercised when it is employed. As a variant of the bromine oxidation it has been proposed to use bromine releasing agents as, for example, those disclosed in U.S. Pat. No. 2,611,700 for this purpose. Also, the use of hypobromides or mixtures of bromate ions and hydrobromic acid have been disclosed as in U.S. Pat. No. 2,611,699. None of these methods has found wide application, either because of the caustic and corrosive nature of the compounds or the bromine released or because of their high cost or because of the involved manipulation required.

Recently ozone oxidation has come into commercial usage (see T. W. Bober and T. J. "The Regeneration of Ferricyanide Bleach Using Ozone" — Parts I and II, Image Technology, Vol. 14, No. 4—p. 13; No. 5—p. 19 [1972]). The article describes large scale regeneration trials on Process CRI-1 and Process K-12 bleaches using ozone, and suppliers of complete factory-built

30 systems for bleach regeneration are given. However, there is a difficulty with the ozone oxidation in that the equipment used for generation of ozone has a high initial capital cost and a high operation cost. Moreover, generation of ozone is inefficient in terms of energy conversion. Still further, the formulations for ozone generation are rapidly being changed so that often generating equipment is obsoleted before its initial cost can be fully amortized.

Another approach to the regeneration of ferrocyanides has been by the use of peroxides and per-acids, but in such cases the bleach must be made very acidic for the reaction to proceed rapidly and to completion. The high acidity results in undesirable side reactions and unduly complicates the regeneration of ferricyanide.

At the present time the most widely practiced method for converting ferrocyanide to ferricyanide utilizes a water-soluble persulfate as the regenerating agent. The latter method has several advantages. Capital outlay is low, the method is relatively safe and it is simple to use. However, it suffers several drawbacks, the most serious of which is the formation of sulfate ions as a by-product of regeneration. These ions reduce the efficacy of the bleaching action of the ferricyanide on metallic silver grains, the reduction being so serious that after four or five regeneration cycles the bleach has to be discarded. It is not currently feasible to inexpensively remove the sulfate ions so as to restore the usefulness of the bleach. As the sulfate ion concentration increases, saturation eventually is approached and in some portions of the system, e.g. a tank, or in some of the lines, crystallization occurs. To avoid this, users of persulfate for silver bleach regeneration frequently discard a portion of each batch of recycled bleach and replace it with an equal volume of sulfate-free bleach. Typically, the loss incurred in 10% or more of an average recycled volume of bleach. Perhaps a more impor-

55

60

65

tant consequence of a high sulfate concentration in the bleach is the necessity for a higher equilibrium concentration of ferricyanide than would be necessary if sulfate ions were not present. A cursory comparison of sulfate-free with sulfate-containing bleaches indicates that the ferricyanide concentration for a sulfate-ion-free bleach for an equivalent rate of bleaching is about 30% less than for a bleach containing a saturation quantity of sulfate ions.

Also involved in connection with ferricyanide silver bleaches and in which the spent bleaches contain ferrocyanide as well, and which, for example, with the persulfate regenerating process require discarding of bleach fractions to keep the sulfate ion concentration at an acceptable level, is that economic and convenience factors are not the only governing considerations as they once were. In the present day, the demands of ecology require that pollution be kept to a minimum. Ferricyanide and ferrocyanide can decompose to form cyanide when such solutions are dumped either into a sewer or a running or quiescent body of water. Due to the large concentration of these ions in bleach effluent, maximum allowable cyanide concentrations which represent the limits for the sewer codes in many municipalities are exceeded far too easily, so that given the present state of affairs, pollution abatement has become the deciding factor and regeneration is often the only acceptable alternative.

SUMMARY OF THE INVENTION

1. Purposes of the Invention

It is an object of this invention to provide for regenerating spent photographic silver bleaching solutions a method which avoids all the foregoing drawbacks.

It is another object of the invention to provide a method of the character described which will regenerate spent ferricyanide/ferrocyanide-containing photographic bleaching solutions with a low capital outlay and low maintenance costs, and with an ability to be operated by personnel of low skill.

It is another object of the invention to provide a method of the character described which can be practiced economically and safely and, withal, is rapid and efficient.

Other objects of the invention in part will be obvious and in part will be pointed out hereinafter.

2. Brief Description of the Invention

In accordance with the present invention, a spent photographic silver bleach solution is regenerated by reacting such solution with an alkali metal halite to oxidize ferrocyanide ions to ferricyanide ions. The desired halite is a bromite. The reaction proceeds best at a pH in the neighborhood of neutrality. More specifically, it will proceed rapidly and apparently stoichiometrically between a pH of about 6 and a pH of about 8. It has been observed that at a pH of above 8.5 the regenerating reaction approaches a standstill.

The oxidation reaction of the halite on the ferrocyanide ions generates hydroxyl ions which tend to raise the pH of the solutions beyond the acceptable range. Moreover, sodium bromite is not considered stable enough to store in dry form. It can decompose violently on contact with organic matter and acids, so that for safe handling it is customary to ship it diluted in a dilute aqueous solution of sodium hydroxide, for instance, at 3.5% sodium hydroxide water solution containing about 6 to 8% of sodium bromite. This, too, therefore, is strongly alkaline and tends to raise further the pH of

the spent photographic silver bleach solution being regenerated. To prevent these two alkalizing effects, it is desirable to compensate for the rise in pH by including an acid in the regenerating reaction. Any acid is useful for example, a 10% water solution of an orthophosphoric acid. A preferred acid is hydrobromic acid because it does not add any extraneous ions to the system and, indeed, provides a bromide ion which is useful in the system.

- 10 It is of passing interest to observe that the same reaction, which essentially is an oxidation of the ferrocyanide constituent of the spent photographic silver bleaching can be used for the manufacture of an alkali metal ferricyanide starting from an alkali metal ferrocyanide, or as a method of preparing a fresh ferricyanide bleach starting with a composition including an alkali metal ferrocyanide as all or part of the amount of cyanide eventually desired to be present as a ferricyanide.
- 15 The invention consists in the series of steps which will be exemplified in the method hereinafter described and of which the scope of application will be indicated in the appended claims.

25 PREFERRED EMBODIMENT OF THE INVENTION

A spent photographic bleach solution, this being a solution in which the amount of ferrocyanide is great enough, as is well known, to reduce the rate of bleaching to an unacceptable level, is regenerated in accordance with the present invention by treating such a solution with a water solution containing an alkali metal halite, preferably in the presence of an acid, desirably a mineral acid, and most desirably hydrobromic acid so as not to unnecessarily introduce extraneous ions into the bleaching solution. The regenerated bleach formed is substantially equivalent to the fresh bleach of a like composition. By selecting a preferred halite, to wit, a bromite, and a preferred acid, undesirable foreign ions are not added to the bleach solution, minimum time is required for completion of the regeneration, the regeneration is relatively safe and inexpensive and the method virtually eliminates bleach overflow disposal problems. The presumed overall ionic reaction is:

50 Experimental evidence suggests a two-step reaction expressed ionically as follows:

The conversion of ferrocyanide to ferricyanide proceeds quite rapidly and apparently stoichiometrically between a pH of about 6 and a pH of about 8.

60 To practice the conversion of an alkali metal ferrocyanide to an alkali metal ferricyanide, pursuant to the instant invention there is added to an aqueous ferrocyanide solution a stoichiometric amount of bromite, for example, in the form of sodium bromite. As indicated previously, the sodium bromite which is a very strong oxidizing agent is not sufficiently stable to be safely stored dry and, therefore, is supplied commercially as an alkalized dilute water solution of sodium bromite, for example, a 6 to 8% sodium bromite water solution containing 3.5% sodium hydroxide. Such a solution is

commercially available from Olin Corporation under the trademark "Preptone". Where such a stoichiometric amount of bromite is added to an unbuffered ferrocyanide solution and the pH is adjusted to neutrality with hydrobromic acid, the conversion of ferrocyanide to ferricyanide is essentially complete within about 15 minutes. It has been observed, however, that the pH of the regenerated solution rises and continues to rise for up to about 6 hours, suggesting that the first-mentioned reaction of the above twostage reaction is rapid and the second one is slow.

The invention is practiced in connection with a photographic ferrocyanide/ferricyanide spent bleach solution by adding to such a spent solution wherein the amount of ferrocyanide has previously been ascertained a stoichiometric amount of bromite, again in the form of sodium bromite, e.g. supplied as "Preptone," and again adjusting the pH to between about 6 to about 8 with hydrobromic acid. The amount of hydrobromic acid employed will depend upon the specific composition of the particular bleach solution and the degree of its exhaustion.

Where a buffered bleach is regenerated the pH rise is greatly depressed, that is to say, does not rise as rapidly as where the method is practiced with an unbuffered ferrocyanide solution, and the recorded pH changes usually are complete within approximately 30 minutes. The conversion of the ferrocyanide ions to ferricyanide ions is complete within 10 minutes or less.

The invention may be used with any of the conventional ferricyanide bleach solutions that commonly are used for photographic processing such, for example, as those employed in color film processing for the bleaching step and those employed in reversal black and white processing for the bleaching step. These bleaches typically include aqueous solutions containing an alkali metal ferricyanide such as potassium ferricyanide ($K_3 Fe [CN]_6$), sodium ferricyanide ($Na_3 Fe [CN]_6$), lithium ferricyanide ($Li_3 Fe [CN]_6$) or ammonium ferricyanide ($[NH_4]_3 Fe [CN]_6$), and an alkali metal bromide. Mixtures of these ferricyanide salts also may be used.

As mentioned above, the alkaline halite salts usable in the instant regeneration process are not available or safe in dry form but they are commercially available as aqueous solutions thereof, usually dilute aqueous solutions, typical solutions having from about 6% to about 8% of the halite salt dissolved therein. Such is the case with sodium bromite which is the desired halite of this invention. Moreover, for the purpose of maximizing the chemical stability of alkali metal and sodium halites, it is customary to make such solutions very alkaline, e.g. with sodium hydroxide, a typical amount of sodium hydroxide employed being 3½% by weight. Such commercially available halite aqueous solutions are quite satisfactory for use in connection with the method of the present invention.

The excess alkalinity of the available commercial solutions, as well as the alkalinity produced during the course of the reaction, which tend to raise the pH of the reacting solutions to above 8 this being in excess of the range at which the change from ferrocyanide to ferricyanide proceeds rapidly, can be and, pursuant to the present invention, is offset with either a mineral acid or an organic acid or an acid buffering agent. Inasmuch as conventional ferricyanide bleaches normally contain buffering agents to control the pH of the bleach, the selection of the neutralizing acid should be done bearing

in mind the quantity and constitution of the buffering agent which is present in the bleach being regenerated. For example, if the bleach being regenerated contains a phosphate buffer system therein, the preferred acid utilized in the regenerating system of the present invention for the neutralization of excess alkalinity desirably would be orthophosphoric acid. Another desirable acid use for the foregoing purpose is hydrobromic acid.

The following example has been set forth to aid in understanding the use of the present invention.

A typical standard photographic bleach for the bleaching of color reversal film has the following formula:

Potassium ferricyanide	56 g
Potassium bromide	16.5 g
Sodium phosphate	22 g
Water to	one liter
pH	6.90

This bleach was used to replace the conventional bleach used in the Ektachrome E-3 process. The above formula gave photographic sensitometric results equivalent to those employed with the replaced formula. The film used was Ektachrome sheet film. The aforesaid film after having been exposed in a camera was processed at a rate of 2 square feet per gallon per process cycle using conventional solutions that are employed in the Ektachrome E-3 process except for the bleach solution which was replaced, as just indicated, with the above solution. All other solutions were replenished in accordance with Eastman Kodak instructions which are standard and well known in the art.

After eight process cycles, which is the equivalent of approximately 17 square feet of film per gallon of the substituted bleach, the bleach was analyzed and thereafter regenerated with the aforesaid sodium bromite solution ("Preptone" which has been described earlier). A certain amount of dilution occurred from wash water carried over from the processing step previous to the bleach step; such dilution losses were made up before or after each regeneration by adding potassium ferricyanide and potassium bromide and the pH was adjusted during each regeneration with orthophosphoric acid.

The aforesaid sequence was repeated until 47 square feet of film per gallon of bleach had been processed; this, of course, included intermediate regeneration steps with sodium bromite solution.

The following table is a summary of the chemical composition of the bleach at the various processing stages:

	Potassium Ferricyanide (g/l)	Potassium Ferricyanide added to make up for dilution (g/l)	Potassium Bromide (g/l)
Start	56.0		16.5
Before first regeneration	38.3	9.4	
After first regeneration	55.5		16.2
Before second regeneration	41.0	9.6	
After second regeneration	56.8		17.1
Before third regeneration	46.5	7.5	
After third regeneration	56.3		17.9

The pH of the bleach was adjusted to 6.9 ± 0.1 during and after each regeneration. Sensitometric gray-scale control strips were processed with each process cycle

and, other than normal run-to-run variability, no significant density differences occurred during the course of the test. The dye maximum density area of the control strips were also read on a Westrex RA 1100B sound densitometer and no significant differences in density readings appeared over the duration of the test. Chemically, the bleach at the end of the regeneration series was essentially the same as at the beginning of processing with no build-up of interfering foreign ions.

The quantitative details of the aforesaid example included first assaying the sodium bromite solution.

Commercial sodium bromite solutions contain 60-80 grams per liter of active ingredient and 32-34 grams per liter of sodium hydroxide; the carrier is water. These solutions are moderately stable but should be analyzed for bromite prior to use because some decomposition may occur.

Materials used to analyze for bromite are: a water solution of a reagent grade potassium iodide prepared by dissolving 100 grams of potassium iodide in water and diluting with water to one liter (the water is either distilled water or deionized water); a reagent grade of a phosphate buffer prepared by dissolving 300 grams of crystalline monobasic sodium phosphate ($\text{NaH}_2\text{PO}_4 \cdot \text{H}_2\text{O}$) in water and diluting with water to one liter, the water again being distilled or deionized; and a reagent grade of 0.1000N aqueous solution of sodium thiosulfate.

The method of sodium bromite analysis constitutes pipetting 1 ml. of sodium bromite solution into a 250 ml. Erlenmeyer flask containing 100 ml. of water which is distilled or deionized and adding thereto 20 ml. of the 10% potassium iodide solution and 20 ml. of the phosphate buffer solution. Next, the mixture is titrated with the 0.1000N sodium thiosulfate solution until the mixture is lemon yellow. Finally, a drop or two of a reagent grade soluble starch indicator is added and the mixture is titrated to a colorless endpoint.

The general equation employed for calculating for sodium bromite content is as follows:

$$\text{g/liter NaBrO}_2 =$$

$$\frac{[\text{ml Na}_2\text{S}_2\text{O}_3][\text{N Na}_2\text{S}_2\text{O}_3][\text{Equivalent wt. of NaBrO}_2]}{\text{volume of sample}}$$

Particularizing the above general equation to the aforesaid parameters, the sodium bromite assay in grams per liter equals:

$$[\text{ml Na}_2\text{S}_2\text{O}_3][\text{N Na}_2\text{S}_2\text{O}_3][33.7]$$

It also is necessary in carrying out the present invention to assay the spent bleach for ferrocyanide and ferricyanide content before regenerating the same. This may be done spectrophotometrically by the following method.

The equipment and reagents used are: a Beckman DB spectrophotometer or an equivalent device equipped with 10 mm. cuvettes; a reagent grade 2% sodium bicarbonate solution prepared by dissolving 20 g. of sodium bicarbonate in distilled or deionized water and diluting with distilled or deionized water to one liter; a reagent grade potassium ferricyanide solution prepared by diluting 0.2 g. of potassium ferricyanide ($\pm$

0.1 mg) to one liter in a 2% sodium bicarbonate solution of distilled or deionized water; and a reagent grade potassium persulfate solution prepared by diluting 1.2 g. of potassium persulfate to one liter with a 2% sodium bicarbonate solution of distilled or deionized water.

The method for analyzing for potassium ferricyanide constitutes diluting the spent bleach sample in two steps, the first of which consists in pipetting 3 ml. of the sample into a flask and diluting to 100 ml. with the 2% sodium bicarbonate solution; the second step consists in pipetting 5 ml. of the resulting dilute solution into a flask and diluting a second time to 100 ml. with the 2% sodium bicarbonate solution. The absorbance of the twice-diluted spent bleach sample is read on the spectrophotometer at 420 nm. using a 10 mm. cuvette and using the 2% sodium bicarbonate solution as a blank. The absorbance of the standard potassium ferricyanide solution is read in a similar manner, i.e. after double dilution as aforesaid.

The calculation for potassium ferricyanide employs the following equation:

$$\text{Potassium ferricyanide} = \frac{[\text{grams/liter}]}{}$$

$$\frac{[\text{sample}]}{\text{absorbance}} \frac{[\text{g/l K}_3\text{Fe}(\text{CN})_6 \text{ in standard solution}]}{\text{standard absorbance}} \frac{[10,000]}{15}$$

The method for analyzing for sodium ferrocyanide decahydrate constitutes diluting the spent bleach sample in two steps, the first of which consists in pipetting 3 ml. of the sample into a flask and diluting to 100 ml. with the 2% sodium bicarbonate solution; the second step consists in pipetting 20 ml. of the resulting solution into a bottle and adding by use of a pipette 20 ml. of the potassium persulfate solution. The bottle is closed with a glass stopper, shaken well and allowed to stand at 20°-25°C for one hour, whereupon 10 ml. of the reaction mixture is pipetted into a flask and diluted to 100 ml. with the 2% sodium bicarbonate solution. Now the absorbance of the reaction mixture is read on the spectrophotometer at 420 nm. using a 10 mm. cuvette and using the 2% sodium bicarbonate solution as a blank.

The absorbance of a similarly twice-diluted and similarly treated standard potassium ferricyanide solution is read in the same fashion.

After having determined the potassium ferricyanide content of the bleach by the previous method, the total ferricyanide present after full conversion of the ferrocyanide is obtained by the following formula:

$$\text{Total potassium ferricyanide} = \frac{[\text{reaction mixture absorbance}]}{[\text{grams/liter}]} \frac{\text{g/l K}_3\text{Fe}(\text{CN})_6 \text{ in standard solution}}{\text{standard absorbance}}$$

$$\left[\frac{100}{3} \times \frac{40}{20} \times \frac{100}{10} \right]$$

To determine the sodium ferrocyanide decahydrate content, the following formula is employed:

$$\text{grams/liter sodium ferrocyanide decahydrate} = \frac{\text{total potassium ferricyanide} - \text{initial potassium ferricyanide [g/l]}}{329} \times \frac{484}{484}$$

After completion of the assays, a calculation is made of the volume of sodium bromite (in liters) required for regeneration.

This amount is equal to the number of grams of sodium ferrocyanide decahydrate to be regenerated multiplied by the equivalent weight of sodium bromite (33.7) and divided by the multiple of the equivalent weight of sodium ferricyanide decahydrate (484) and the grams per liter of sodium bromite found by the aforementioned assay. The equation employed is:

$$\text{Vol. bromite} = \frac{\text{sodium ferrocyanide decahydrate [g/l]} \times 0.0696}{\text{bromite assay [g/l]}}$$

Next in the practice of the invention the quantity of sodium bromite solution required to oxidize all the ferrocyanide to ferricyanide, e.g. calculated in the foregoing manner is added to the spent bleach solution and the pH of the solution in which the ferrocyanide is being oxidized is adjusted to neutrality with an acid, e.g. an orthophosphoric acid or hydrobromic acid. The acid employed preferably is added in a water solution and may be quite concentrated. For example, when using hydrobromic acid a 48% aqueous solution thereof is employed. The neutralizing acid is not premixed with the alkaline sodium bromite solution.

The bleach is now regenerated and as a check for efficient reuse the regenerated bleach is assayed for each of its constituents such, for example, as ferricyanide, bromide and other addenda normally present in a fresh bleach. Standard analytical assay methods are employed. It will be recalled that during the bleaching method the bleach solution in the bleaching tank is diluted by carry-over of solution from the preceding tank and it is this which necessitates the aforesaid assay of the constituents of the regenerated bleach.

Finally, additional compounds are added to make up the differences caused by dilution or use, the added compounds being solid or water solutions of potassium ferricyanide, sodium bromide and other addenda as are required.

The foregoing description of the method of the invention provides all the instructions necessary to carry out said method. Nevertheless, to complete the description, there is set forth below an example of a quantitatively described series of steps for regenerating a spent ferricyanide bleach solution, i.e. one containing some ferrocyanide:

To 440 milliliters of an exhausted ferricyanide bleach, found by analysis to contain 101 grams per liter of sodium ferricyanide, $\text{Na}_3\text{Fe}[\text{CN}]_6 \cdot \text{H}_2\text{O}$, and 84 grams per liter of sodium ferrocyanide, $\text{Na}_4\text{Fe}[\text{CN}]_6 \cdot 10\text{H}_2\text{O}$ [47 grams per liter of sodium ferrocyanide, $\text{Na}_4\text{Fe}[\text{CN}]_6 \cdot 10\text{H}_2\text{O}$, were present and 37 grams per liter of sodium ferrocyanide, $\text{Na}_4\text{Fe}[\text{N}]_6 \cdot 10\text{H}_2\text{O}$,

were added], and a pH of 7.86, there were added 36 ml. (a stoichiometric quantity) of a 7% solution of sodium bromite, pH 13 to 14 (Preptone) and 24 milliliters of 4N hydrobromic acid. The sodium ferrocyanide, $\text{Na}_4\text{Fe}[\text{CN}]_6 \cdot 10\text{H}_2\text{O}$, was added to raise the eventual concentration of ferricyanide in the exhausted bleach to the concentration normally found in a fresh bleach. After one hour at room temperature the bleach solution was analyzed and found to have a volume of

10 500 milliliters and contain 132 grams per liter of sodium ferricyanide, $\text{Na}_3\text{Fe}[\text{CN}]_6 \cdot \text{H}_2\text{O}$, as compared to 133 grams per liter of sodium ferricyanide, $\text{Na}_3\text{Fe}[\text{CN}]_6 \cdot \text{H}_2\text{O}$, if all the ferrocyanide in the exhausted bleach had been converted to ferricyanide. The pH of the regenerated solution was 7.92 as compared to a pH of 8.0 for a fresh bleach.

The step of halitizing as described in detail above can be employed to produce an alkaline ferricyanide from an alkaline ferrocyanide as a method for producing sodium ferricyanide apart from a bleach, and the same halitizing step can be used to prepare a ferricyanide bleach starting from a ferrocyanide base, i.e. a bleach in which the cyanide is present principally as a ferrocyanide and is converted to a ferricyanide for commercial use of the bleach.

Certain bleach addenda react with alkali halites. For example, sodium thiocyanate is completely destroyed by reaction upon the addition of a bromite to a bleach containing the same. Hence, this compound must be eliminated from any bleach formula regenerated by the technique of the present invention. Carbowax 1,540 (a polyethylene glycol) is not noticeably affected by sodium bromite. It has been observed that when a sodium bromite solution is mixed with a 50% Carbowax 1,540 solution for a week, there is some slight oxidation of the Carbowax; but since this is not a procedure which would be followed with the use of the present invention, it is not necessary to employ bleach formulations with Carbowax eliminated.

The use of the invention has not appeared to cause any dye degradation on color film which has been bleached by a regenerated bleach solution.

The present invention also is useful to regenerate potassium ferricyanide bleaches such, for instance, as an ME-4 type of ferricyanide bleach. An ME-4 ferricyanide bleach replenisher and fresh bleach usually contains about 160 g/l of potassium ferricyanide. The average concentration of potassium ferricyanide present in a tank of spent bleach following the ME-4 process is 112 g/l and the equilibrium tank concentration of ferrocyanide is about 30 g/l as potential potassium ferricyanide. In the practice of the invention enough bromite is added to convert about two-thirds of the ferrocyanide to ferricyanide, to wit, about 20 g/l, and about 30 g/l of dry potassium ferricyanide is added to raise the total potassium ferricyanide concentration after regeneration to the desired 160 g/l level.

The cost of using a halite such as sodium bromite for regeneration of a spent ferricyanide photographic silver bleach solution is higher than that for regeneration with a persulfate solution, but the additional cost is largely negated by eliminating the need for discarding a portion of bleach solution when persulfate regeneration is utilized in order to prevent a build-up of sulfate. Moreover, by using a halite for regeneration ferricyanide losses to the environment can be minimized and

substantially eliminated because the system is amenable to closedloop operation.

It thus will be seen that there is provided a method which achieves the various objects of the invention and which is well adapted to meet the conditions of practical use.

As various possible embodiments might be made of the above invention, and as various changes might be made in the embodiment above set forth, it is to be understood that all matter herein described is to be interpreted as illustrative and not in a limiting sense.

Having thus described the invention there is claimed as new and desired to be secured by Letters Patent:

1. A method of regenerating a photographic aqueous spent silver bleach solution containing an alkali ferrocyanide, said method comprising adding to the silver bleach solution an aqueous solution containing an alkali metal bromite to oxidize ferrocyanide ions to ferricyanide ions, the oxidation being carried out at a pH of between about 6 and about 8 at room temperature.

2. A method as set forth in claim 1 wherein the alkali metal is sodium.

3. A method as set forth in claim 1 wherein the pH is maintained in the range of between about 6 and about 8 by the addition to the spent silver bleach solution in which the ferrocyanide is being oxidized of an acid selected from the group consisting of orthophosphoric acid and hydrobromic acid.

4. A method as set forth in claim 3 wherein the alkali metal bromite is in water solution and wherein said water solution also contains an alkalinizing agent.

5. A method as set forth in claim 4 wherein the alkalinizing agent is an alkali metal hydroxide.

6. A method as set forth in claim 5 wherein the alkali metal hydroxide is sodium hydroxide.

7. A method as set forth in claim 6 wherein the pH of the alkaline water solution of the alkali metal bromite is at least 13.

8. A method as set forth in claim 1 wherein the amount of alkali metal bromite added to the spent silver bleach solution is about equal to that necessary to stoichiometrically react with all the ferrocyanide ions to convert them to ferricyanide ions.
